FLOAT VALVE FOR WATER DISPENSERS

Joseph Continenza, Stuart, Fla.

Application April 12, 1950, Serial No. 155,428

2 Claims. (Cl. 137—445)

1

This invention relates to a float valve, particularly adapted for embodiment in a cold water dispenser for refrigerators.

An important object of the present invention is to provide an improved float valve construction for water dispensers, that will be of simple and easily assembled construction, will permit adjustment to regulate the normal water level in the dispenser, and that will permit adjustments to be readily made with respect to the tightness with which said valve will engage its seat in the closed position of the valve.

Another important object of the present invention is to provide an improved means mounted in a refrigerator whereby one is permitted to draw cold water from a tap mounted in association with said refrigerator, the cold water drawn from said tap being chilled within the refrigerator, which refrigerator can be the conventional domestic type of electric refrigerator.

Another important object is to provide a dispenser of the type stated which will operate automatically to maintain a supply of water therein that will be chilled by the refrigerator, so that ice water will be dispensed from the device at all times.

Still another object is to provide a device of the type stated that can be mounted in a refrigerator already in use, without modification of the form of said refrigerator.

Yet another object is to provide a device of the type stated which will be capable of manufacture at relatively low cost, durable, and sanitary.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Fig. 1 is a vertical section through the device and through a portion of a refrigerator in which the device is mounted.

Fig. 2 is an enlarged section on line 2—2 of Fig. 1.

Fig. 3 is an enlarged section on line 3—3 of Fig. 1.

Fig. 4 is an enlarged fragmentary perspective view of a pivoted float-supporting arm.

Fig. 5 is a perspective view of a plunger reciprocated by said arm.

2

Referring to the drawings in detail, a conventional domestic refrigerator 1 is provided with an opening in its wall through which extends a pipe 2 tapped into the house water supply. Pipe 5 2 at its inner end extends into communication with a reduced bore 3 formed in a valve body 4, said bore 3 extending to the shut-off valve chamber 5 in which is threadably engaged the shut-off valve 6 capable of manual operation to close off bore 3 whenever desired.

Extending from the valve chamber 5 is the reduced vertical bore 7 opening at its lower end into the counterbore 8 the base of which is convex as at 9, the bore 7 opening into the crest of 15 the convex seat 9. The counterbore 8 opens upon the lower end of the valve body 4, said lower end of the valve body being externally threaded. A convex rubber washer or valve head 10 is disposed just below the convex seat 9, and the crest 20 of said rubber head 10 is adapted to engage against the bore 7 when the head is shifted upwardly to shut off the passage of water through said bore 7.

The rubber head 10 is secured to the enlarged 25 upper end 11 of a pipe member 12 having near its lower end the diametrically opposed cut away portions 14. The plunger is reciprocable in the bore of a tubular bracket 15 having the ear 16 laterally extended therefrom on which pivots in 30 a vertical plane the float support arm having the yoke 17 at one end straddling the bracket 16 and pivotally connected to said bracket; said yoke being formed at the upper end of the upwardly extended portion 18 of the float support arm, said upwardly extended portion being at right angles to the intermediate portion 19 of said arm, and being twisted perpendicularly relative to said intermediate portion 19.

The intermediate portion 19 of the float support arm (Fig. 4) has formed therein the longitudinal slot 20 having at one end the circular enlarged portion 21. The plunger 12 is entered through the enlarged portion 21 until the cut away portions 14 align with the intermediate portion 19, after which movement of the plunger lengthwise of the float supporting arm causes the side walls of the elongated slot 20 to locate between the top and bottom shoulders defined by the recesses 14 of the plunger. This connects the plunger and float support arm without the necessity of special connections, so that swinging of the float support arm upwardly or downwardly upon the supporting bracket 15 causes vertical reciprocation of the plunger 12.

55 The other end of the float support arm is

twisted at 21' into perpendicularity to the intermediate portion 19, and is extended obliquely and upwardly relative to the substantially horizontally disposed intermediate portion of the float support arm, as at 22. A longitudinal series of openings 23 are formed in said free end of the float support arm, and pivotally connected to the upwardly extended end 22 of the arm through any of the openings 23 is the depending link 24 secured at its lower end to the female stud 25 attached to the removable lid of a cup-like float 26 floating in a supply of water contained in the lower portion 27 of the cold water container. The lower portion 27 of the container is removably engaged with the fixed upper portion 28 into which the pipe 2 extends, and said lower portion of the container is supported upon a shelf 29 of the refrigerator being removably connected to said shelf by means of a screw and wing nut 30. A tap 31 is mounted in the wall of the container 27 adjacent the lower end thereof.

In use, it will be understood that overall control of the device is possible through the medium of the shut-off valve 6, and the device can be rendered inoperative by closing of said valve as in Fig. 1. Assuming that the device is to be placed in use the valve 6 is opened and left open.

When the water level W drops, the float support arm will be pulled downwardly, and will in turn pull the reciprocable plunger 12 downwardly so as to open the bore 7. Water will be forced under pressure through pipe 2 through the bore 3, valve chamber 5, bore 7, around the head 10 and externally of the plunger 12 and thence into the container. The water will continue to raise the water level until the flow 26 has risen to an extent sufficient to once more engage the rubber head 10 in the position of Fig. 1, in which position it closes the bore 7 and shuts off the inflow.

It may be noted that the plunger 12 from one end to the other is of substantially reduced diameter relative to the counterbore 8 and the bore of the tubular bracket 15, thus to permit the water to flow externally of said plunger after it leaves the bore 7.

In this way a continuous supply of water W is maintained, sufficient to cause said water to be chilled by normal operation of the household refrigerator, so that each time the tap 31 is opened by a user, ice cold water will be dispensed.

The level of the water in the container is adjustable by adjustable positioning of the link 24 relative to the float support arm, the longitudinal series of openings 23 being intended for this purpose.

What is claimed is:

1. In a float valve construction for a water dispenser, a valve body adapted to be fixedly mounted within a dispenser container, said valve body having a vertical bore and having a counterbore below and in communication with said vertical bore, the lower end of said valve body being externally threaded; a tubular bracket having a vertical bore coaxial with the bore and counterbore of the valve body, said tubular bracket being internally threaded at its upper end for adjustable connection to the threads of the valve body; an ear projecting laterally from and rigid with said bracket; a plunger member vertically reciprocable

in the bore of the bracket and formed at its upper end with a valve head disposed within said counterbore, said valve head being engageable in the upper position of the plunger member against the base of the counterbore, whereby to close the bore of the valve body; a float support arm having a horizontal intermediate portion connected with said plunger member, one end portion of said float support arm being rigid with said intermediate portion and extending upwardly from said intermediate portion in approximate parallelism with said plunger member, said end of the float support arm being pivotally connected to the ear of the bracket; and a float connected to the other end of the float support arm, the bracket when threaded upwardly upon the valve body bodily carrying therewith the plunger member and float support arm, whereby to control the seating of the valve head against the base of the counterbore.

2. A valve comprising an elongated valve body, a nipple carried by the valve body and projecting downwardly therefrom intermediate the ends thereof, said nipple having an axial discharge orifice extending therethrough and an axially disposed bore opening through its lower end communicating with the discharge orifice, an elongated fitting having a vertically disposed axial passage extending therethrough and communicating with the bore in the nipple, an ear carried by the fitting and extending laterally therefrom above the lower end thereof, a float support arm pivotally connected to the ear and extending downwardly therefrom adjacent the fitting, an extension on the float support arm and projecting laterally therefrom beneath the fitting, said extension having an elongated longitudinally extending keyhole slot extending therethrough intermediate its ends, an elongated plunger mounted in a fitting for movement vertically therein and adapted to enter the enlarged portion of the keyhole slot, said plunger having diametrically opposed grooves extending transversely thereof for receiving opposite walls of the keyhole slot, a head carried by the plunger into closing relation to the discharge orifice, and a buoyant body carried by the extension remote from the float support arm for rocking said arm about the pivot and moving the head into and out of closing relation to the orifice.

JOSEPH CONTINENZA.
